DISPENSING DEVICE

Paul J. Ulibarr, Los Angeles, Calif.

Application August 5, 1940, Serial No. 351,500

3 Claims. (Cl. 312—84)

This invention relates to a dispensing device, and more particularly to a device for singly dispensing small elongated articles, for example, tooth picks, matches, pencils or cigarettes.

More specifically speaking the invention pertains to a simplified construction of a support provided with a hopper, in combination with an elongated member which is turnable about its axis and which is provided with an elongated longitudinally extending seat spaced radially from its axis, to receive from said hopper and singly dispense articles fed therefrom.

The invention further pertains to the combination with said turnable member of an improved and simplified supporting means therefor, said supporting means being provided with a downward extension which forms a superior track means to convey the dispensed articles to a point where they are readily manually accessible.

Other objects, advantages and features of invention will hereinafter appear.

Referring to the accompanying drawing which illustrates what is at present deemed to be a preferred embodiment of the invention,

Fig. 1 is a front elevation of the device, parts being shown in section. The line 1—1 on Fig. 2 indicates the plane of the sectioned portion of the view.

Fig. 2 is a vertical section, the plane of section being indicated by the line 2—2 of Fig. 1.

Fig. 3 is a plan view of the structure shown on Figs. 1 and 2.

Fig. 4 is a side elevation of a portion of the structure illustrating one of the operating cranks together with the stop means and guard for said crank.

Fig. 5 is a view illustrating in side elevation, by way of example, the kind of articles ordinarily dispensed by the device.

Fig. 6 is a detail view of a portion of the device.

Referring in detail to the drawing, the device is provided with side walls 10 and 11 each of which is provided with an outwardly directed annular flange 12 which forms a bearing for shafts 13, the outer end portions of which are bent to form the cranks 15. The inner end of each shaft 13 is furnished with a bifurcation 13x to anchor it within the member 13 and to maintain it non-rotatable in relation thereto. The cylindrical member 14 may be made of wood, which will cause the bifurcations 13x to widen as the shafts are driven in.

Upon said member 14 is mounted a split sleeve 20 which is of a somewhat resilient character and which grips the member 14 with a friction tight

fit. When the sleeve is in place upon the member 14 a space is formed by the split therein and this space is utilized as a pocket or recess to receive singly the articles dispensed from the hopper portion of the device.

In order to provide a suitable hopper to deliver the dispensed articles to said pocket 21, with the side walls 10 and 11 are combined the front wall 25 and the rear wall 26; and the front wall 25 is provided with an inclined downward extension 27 which forms the front part of the bottom of the hopper. The rear part of the hopper bottom is formed by an inclined plate 28, said plate 28 having a downwardly continued segmental portion 29 which underlies about one-third of the circumference of the sleeve 20, the sleeve nesting closely within this segmental part below the part 29 the plate being continued as an inclined apron 30 supporting a delivery track 30t for the articles being dispensed. The lower end of the track is continued horizontally to form a front portion 32 whereby the dispensed articles are supported for manual removal. An abutment 33 at the front end of said foot portion prevents the dispensed articles from falling off the base member 34 by which the various parts of the device which have been described are supported. Said base member is shown as a plate, either of wood or metal, of a considerable thickness having a recess 35 provided in its upper front portion, said recess affording a convenient finger-hold space to enable the operator to more conveniently withdraw the dispensed articles. The abutment 33 which has been mentioned is of a two-part character, there being a considerable space between the two parts thereof providing ample room for the fingers to be inserted for grasping and removing the pencils, matches or other elongated articles being dispensed.

40 In order to automatically retract the shaft 13 and parts which turn therewith to the original position after a dispensing operation, a spring 37 anchored to the base 34 at its lower end has its upper end secured to the arm 15a of the crank 45 15. A combined guard and stop plate 40 is provided to partially house each crank arm 15a and to provide stop means for limiting its swinging movement. Said plate 40 has angularly directed end portions 41 whereby it is secured to the adjacent side wall of the structure by soldering or other suitable means.

The device is shown furnished with a cover 45 which is flanged to fit over the top thereof, said cover having a handle 46.

In the particular embodiment of the invention

illustrated in the drawing, the turnable dispensing element is shown shaped in such a manner so as to dispense matches, or other elongated articles each of which has an enlargement of some kind at one end. In order to provide room for such an enlargement, the right hand end portion of the cylindrical member 14 is shown diametrically reduced or angularly grooved at 14a so as to provide room for the match head 50 shown in Fig. 1 to overhang from the groove or space 21 (Fig. 2) provided for its body portion. Also a properly positioned notch 52 will be cut in a lower end portion of the inclined hopper wall part 27 to make room for the passage of the head of the match so that its delivery will be unobstructed. So far as any elongated article having an enlarged end portion is concerned, what has been said about matches will apply with equal force to such enlargements as erasers attached to lead pencils, and to other elongated articles shaped or provided with parts which form end enlargements.

Along the inclined back wall 28 of the hopper bottom a channel 28c is shown along the outer side of one of the track rails to afford a clearance for the overhanging headed portions of whatever elongated objects are being discharged from the hopper.

In operation of the device, after the articles to be dispensed have been deposited in the hopper (the heads of the matches or eraser ends of the pencils being placed toward the right side of the device as viewed in Fig. 1) the user will swing either of the cranks 15 upwardly and forwardly until the front stop wall 41 arrests the turning movement thus given to the rotary dispensing element. This will cause whatever article occupies the dispensing pocket 21 to be carried forwardly a sufficient distance to fall upon the apron or track 30 and glide forward until it is stopped by the abutments 33 in a position for convenient manual removal.

Owing to the fact that the resilient sleeve 20

maintains itself friction tight upon the roller 14 in the attached position, no special fastening means is needed to keep it in place. Also a set of sleeves differing somewhat in size and shape may be provided and when it is desired to change the size of the dispensing pocket 21 the sleeve which has been in use may be sprung sufficiently to remove it from the cylinder 14 and after removal be replaced by another sleeve of the desired shape and size. By this means suitable dispensing pockets can be provided for handling either an article like a pencil or match 60, cigar or tooth pick 61 or cigarette or drinking straw 62 illustrated in Fig. 5.

Referring to additional structural details, the rear wall 28 of the hopper has at each side a track rail 28t to facilitate the downward gliding of the elongated articles as they move toward the turnable dispensing element 20.

I claim:

1. In a dispensing device, an elongated member of a generally cylindrical shape, means whereby said member is mounted in a horizontally extending position to turn about its axis, a split sleeve encircling said member and gripping it in a friction tight manner, the split in said sleeve combining with said member to form a dispensing recess, a hopper positioned to deliver elongated articles singly to said recess, and means to partially rotate said member about its axis to dispense articles singly from said hopper.

2. The subject matter of claim 1 and, said cylindrical member having a recessed end portion alining with the split portion of the applied sleeve to make room for end enlargements of elongated articles being dispensed.

3. The subject matter of claim 1 and, said cylindrical member being annularly recessed around at least one of its end portions to make room for end enlargements of elongated articles being dispensed.

PAUL J. ULIBARR.
